HAIR CURLING DEVICE

Blanche Elsie Beadle, Springfield, Mass.

Application July 7, 1934, Serial No. 734,071

13 Claims. (Cl. 132—41)

This invention relates to hair curling devices and has particular reference to devices for rolling up the ends of hair and holding it in rolled form until it sets.

5 Hair curling devices of this type, known generally as "end-curlers", have been made in various forms, all characteristic in that they include a cylindrical body around which the hair is rolled inwardly from its ends, and a locking member pivoted or otherwise attached at one end of the body and detachably connected thereto at its free end for securing the hair in rolled position while the curl sets. Various arrangements have 10 been adopted for detachably connecting the free end of the locking member to the body and these include spring catches which soon lose their resiliency, rubber bands which are rapidly deteriorated by the hair treating oils, liquids and compounds used to set the hair, and other forms 15 of connecting means which do not remain effective.

In accordance with the present invention, a hair curling device of the end curler type is provided which is free from the aforementioned objections in that the free end of the locking member is positively secured to the body, without the use of spring latches, rubber bands and the like, and in such a way that it cannot be detached except intentionally, and does not lose its effectiveness.

30 In the new hair curling device of this invention, the lock between the body and the free end of the locking member is obtained by a relative longitudinal bodily movement between the body and the pivoted locking member, which enables locking cooperation between the corresponding free ends of the body and the locking member, preferably by the insertion of a part of the locking member in the end of the body or vice versa, 35 so that a positive lock is made at an angle to the direction of the closing and opening movements of the pivoted locking member. Elastic bands and spring latches are accordingly dispensed with and a positive but readily releasable lock is 40 provided between the locking member and the body.

More particularly, the new device of this invention comprises a tubular body having a locking member pivoted at one end to one end of the body 45 and bodily movable longitudinally with respect thereto at its pivot point, so that the free end of the member is releasably secured to the free end of the body. For example, the free end of the member may be shaped for insertion into a slot 50 or other opening in the corresponding end of the

body, or the free end of the member may be provided with a ring for encircling the body. The locking member is preferably urged into locking position either by a spring or by a novel resilient end portion of the locking member.

5 In another form of the device, in which a clamping lip is pivoted on the body for initially clamping the hair prior to the application of the locking member, the latter is carried by the lip which is bodily movable longitudinally of the body to move the locking member with it for locking and unlocking cooperation between its free end and the free end of the body in the manner described.

10 In another modification of the invention, the projecting ends of the hinge pin between the body and the lip is perforated for the sliding reception of the inner ends of the locking member, which is accordingly movable bodily longitudinally of the body for locking and unlocking cooperation 15 between its free end and the free end of the body. Alternatively, only one such connection between the locking member and the pivot pin may be 20 employed.

25 Also, the body may be made of metal or a non-metallic material, such as rubber, or metal covered with rubber, and if the body is made of metal the lip may be formed integrally therewith in accordance with this invention.

30 It will be seen that with the present invention in its various forms the objections to the usual types of end curling devices are overcome, and that a very simple, inexpensive, and a device positive in action is provided.

35 For a more complete understanding of the hair curling device of this invention, reference may be had to the accompanying drawing, in which

40 Figure 1 illustrates a preferred form of the invention, in which the locking member is urged in normal locking position by the natural resiliency of its pivot end;

45 Figure 2 is a longitudinal cross-section therethrough, as seen along the line 2—2 of Figure 1;

Figure 3 illustrates a modified form of the device in which the free end of the locking member releasably encircles the corresponding end of the body and is urged into locking position by a spring within the body;

50 Figure 4 is a longitudinal section therethrough, as seen along the line 4—4 of Figure 3;

55 Figure 5 illustrates a modified form of the device in which the lip is slidable longitudinally of the body and carries the locking member;

Figure 6 illustrates another modification in 55

which the lip and body are made of one piece of material; and

Figure 7 is still another modification in which the locking member is slideable through apertures in the pivot pin of the lip.

Referring to Figures 1 and 2 of the drawing, numeral 10 designates a tubular body of metal, such as aluminum, although it may be made of rubber or other non-metallic material, or of metal coated with rubber or other non-metallic material, depending upon requirements. Also, the body may be perforated as indicated, so as to permit air circulation therethrough to facilitate drying of the hair. The lower end of the body is provided with an integral, outwardly-turned finger piece 11.

Pivoted to the body 10 by means of a pivot pin 12, is a lip 13 having a semi-circular contour or a contour conforming to the contour of the outer surface of the body 10, so as to partially embrace the latter. The lower end of the lip 13 is also provided with an outwardly-turned finger piece 14 cooperating with the finger piece 11 of body 10 and normally urged therefrom by a leaf spring 15 engaging the inner surfaces of finger pieces 11 and 14, which are recessed to hold and enclose the spring 15. The lip 13 is accordingly normally urged against the body 10 and serves to clamp the hair which is rolled around the body 10 in the manner of a curling iron.

The body 10 is provided adjacent its pivot pin 12 with opposite openings 16 which serve as pivot points for the converging ends 17 of a generally U-shaped locking member 18, which is preferably made of resilient wire and is inwardly turned at its free end to form locking means 19. The curvature of the pivot ends 17 of the locking member 18 is such that they produce a cam action in openings 16, and the resiliency of the wire 40 of which the locking member 18 is formed urges these ends together, so that when the locking member 18 is drawn upwardly, as seen in Figure 2, the ends 17 produce a self-spring action which tends to urge the member 18 downwardly as seen 45 in Figure 2. Accordingly, locking means 19 is normally urged into the open free end of body 10 when aligned therewith without requiring the use of separate springs for that purpose. Also, the device may be very simply assembled by 50 merely inserting the ends 17 of the locking member 18 into corresponding openings 16 of the body 10, the ends 17 being turned up slightly, as shown in Figure 2, to prevent them from being withdrawn through the openings 16 in use.

55 In utilizing the new hair curling device illustrated in Figures 1 and 2, the locking member 18 is drawn longitudinally of the body 10 to release locking means 19 therefrom and is swung away from the body 10 as is indicated by the arrow 60 in Figure 1. Finger pieces 11 and 14 are grasped between the fingers and pressed together to separate the lip 13 from the body 10 and the end of a strand of hair is clamped between them and the strand is then rolled inwardly from its end 65 upon the body 10. When the hair has been rolled on the body 10, locking member 18 is moved longitudinally of the body 10 to align the locking means 19 with the open end of the body 10. The locking member is then released to permit 70 the locking means 19 to snap into the open free end of the body 10 under the influence of the self-spring action afforded by the free ends 17 of the locking member 18. It will be observed that the sides of the locking member are drawn against 75 the body 10 because of the cam action of ends

17, so that the hair is more securely and evenly held on the body.

In the modification illustrated in Figures 3 and 4, the locking member 18a is formed at its free end with a ring 20 which is adapted to encircle the upper end of the body 10a to serve as the locking means for the locking member 18a. The inner end of the locking member 18a is provided with a transverse bar portion 21 which is slideable longitudinally of the body 10a in elongated slots 22, being normally urged downwardly by means of a coil spring 23 connected at one end to the bar 21 and at its other end to the pivot pin 12a of the lip 13a. It will be seen that by pulling outwardly on the end 20 of the locking member 18a, this end or ring 20 may be aligned with the free end of the body 10a, so that when the locking member 18a is released its spring 23 pulls it downwardly longitudinally of the body 10a, as seen in Figures 3 and 4 to cause ring 20 to encircle body 10a and thus lock the locking member 18a in position. The operation of this form of curler will be understood from the description of the operation of the form illustrated in Figures 1 and 2.

In the form of curler illustrated in Figure 5, the body 10b is formed as before, but the connection between the body 10b and the lip 13b is provided by a pin and slot combination, the pivot pin 12b passing through longitudinal slots 24 formed in opposite ends of the lip 13b. The locking member 18b is pivoted on and is accordingly carried by the lip 13b and is formed with a transverse bar 25 at its free end which is adapted to engage in notches 26 in the free end of body 10b. In utilizing this form of the curler, the hair is wrapped around the body 10b, clamped thereto by lip 13b and locked in place by aligning bar 25 of locking member 18b with notches 26 and moving the lip 13b downwardly longitudinally of the body 10b, as seen in Figure 5, to engage the bar 25 in the notches 26. A spring 23b may be provided within the body 10b for normally urging the lip 13b and with it the locking member 18b in a downward direction as seen in Figure 5.

In the modified form of the curler illustrated in Figure 6, the body 10c and the lip 13c are formed of one piece of metal, preferably aluminum, being joined by the integral connecting piece 27 which is flexible to serve as the hinge permitting the lip 13c to move toward and away from the body 10c. A compression leaf spring 28 is secured at its ends by rivets 29 to the body 10c and to the lip 13c, so as to resiliently urge lip 13c into engagement with body 10c. The body 10c is provided with opposite longitudinal slots 30 through which passes the pivot end of the locking member 18c, the free end of which is provided with a separate metal locking means 31, adapted to be inserted into the open free end of the body 10c when the locking member 18c is moved longitudinally downwardly in slots 30 with the locking means 31 in alignment with the open free end of body 10c. A spring 23c, similar to spring 23 in the form illustrated in Figure 4 may be employed for urging the locking member 18c normally downwardly as seen in Figure 6, although a spring is not essential, because when the rolled hair is spread out along the body 10c it will lock the locking means in position.

In the form of curler illustrated in Figure 7, the body 10d and the lip 13d are connected together by a pivot pin 12d the ends of which project to either side of the corresponding portions of the lip 13d and are each provided with a

transverse perforation. Through each of these perforations slidably passes a leg 32 of the U-shaped locking member 18d. The extreme end of each leg 32 is provided with enlargement 33 which prevents it from being withdrawn from the corresponding perforation in the pivot pin 12d. The free end of the locking member 18d is provided with a downwardly turned means 34 for insertion into the open free end of body 10d when 5 the locking member 18d is moved downwardly as seen in Figure 7. Alternatively, only one of the legs 32 of the locking member 18d with the locking means 34 need be employed, the omitted leg of the body member being indicated by the dotted 10 lines in Figure 7. A suitable cotter pin is inserted in the corresponding perforation in pivot pin 12d to prevent the latter from being withdrawn. In this form of locking member 18d, the locking means 34 is enlarged transversely so that it frictionally engages the inner walls of the body 10d, so as to hold the locking member 18d in locked 15 position. A spring 23d interposed between the enlargement 33 and the pin 12d normally urges the locking member 18d downwardly toward locking 20 position.

It will be understood that the one-piece construction of the body 10c and lip 13c illustrated in Figure 6, may be employed in all forms of the device illustrated except the form of Figure 5, 25 and that the various forms of locking members 18 to 18d, inclusive, may be employed on any of the forms of body and lip combinations illustrated in the various modifications and also that the various forms of locking means 19, 20, 25, 31 30 and 34 may be employed with any of the various forms of locking members 18 to 18d, inclusive.

It will be seen that all of the modifications of the end curler of this invention are characteristic in that the locking member is moved bodily 40 longitudinally of the body to effect locking and unlocking of its free end with the body and that the lock between the free end of the locking member and the body is positive and secure, so that accidental or unintended release of the locking 45 member is impossible, it being necessary for the user to effect positive relative longitudinal movement between the body and the locking member to release them from each other.

While certain preferred embodiments of this 50 invention have been illustrated and described herein, it is to be understood that the invention is not limited thereby, but is susceptible of various changes of form and detail within its scope.

I claim:

1. In a hair curling device, the combination of 55 an elongated body, a locking member pivotally connected at one end to the body adjacent one end thereof and movable longitudinally relative to the body to effect a releasable connection at its free end to the corresponding free end of the body, said releasable connection including a reversely-turned means on the free end of the member insertable in an opening in the free end of the body, and resilient means normally opposing longitudinal movement of said member away from the body.

2. In a hair curling device, the combination of 60 an elongated body, a locking member pivotally connected at one end to the body adjacent one end thereof and movable longitudinally relative to the body to effect a releasable connection at its free end to the corresponding free end of the body, said releasable connection including a ring 65 in the free end of the member adapted to encircle the free end of the body, and resilient means

normally opposing longitudinal movement of said member away from the body.

3. In a hair curling device, the combination of 70 an elongated body on which the hair is rolled, a locking member pivoted at one end to the body adjacent one end thereof and releasably connectable at its free end to the corresponding free end of the body to secure the rolled hair in place thereon, and resilient means connected between 75 said body and member and actuatable in accordance with the connecting movement of the member with the free end of the body for drawing the member laterally toward the body to more tightly secure the rolled hair thereon.

4. In a hair curling device, the combination of 80 an elongated body, and a locking member pivotally connected at one end to the body adjacent one end thereof and releasably connectable at its free end to the corresponding free end of the body, said member having resilient arms with their ends inserted loosely in opposite openings in the body, whereby the resilience of the arms permits bodily movement of the member longitudinally of the body to effect the connection and disconnection of the free ends of the body and member.

5. A hair curling device comprising a single 85 elongated strip of material having one end formed into a hair-rolling body and the other end bent to overlie the body to form a lip, said strip including a resilient portion permitting relative 90 movement of the body and lip, and means associated with said strip for holding the hair in place on the body.

6. A hair curling device comprising an elongated body, a locking member pivotally connected 95 at one end to the body adjacent one end thereof and releasably connectable at its free end to the corresponding free end of the body, said member being movable relative to the body to effect the connection and disconnection of its free end with the body, and means for urging said body and member toward each other when they are in 100 position for connection of their free ends.

7. In a hair curling device, the combination of 105 hair clamping means including an elongated body and a lip hinged to the body adjacent one end thereof, a portion of said lip being normally urged against the side wall of the body, and a locking member pivotally connected at one end to the clamping means adjacent the said one end of the 110 body and releasably connectable at its free end to the corresponding free end of the body, said body and locking member being bodily movable longitudinally of each other to effect the connection and disconnection of their free ends.

8. In a hair curling device, the combination of 115 hair clamping means including an elongated body and a lip hinged to the body adjacent one end thereof, a portion of said lip being normally urged against the side wall of the body, a locking member pivotally connected at one end to the clamping means adjacent the said one end of the body and releasably connectable at its free end to the corresponding free end of the body, said body and locking member being bodily movable longitudinally of each other to effect the connection and disconnection of their free ends, and means for urging the free ends of said body and locking member longitudinally toward each other when said body and locking member are 120 in position for connection of their free ends.

9. In a hair curling device, the combination of 125 an elongated body, and a substantially U-shaped locking member having the ends of its arms extending obliquely into opposite openings in the

body adjacent one end thereof for permitting bodily movement of the locking member longitudinally of the body, said locking member being pivotable with respect to the body and releasably connectable at its free end to the corresponding free end of the body upon relative longitudinal movement of the body and locking member in one direction.

10. In a hair curling device, the combination of an elongated body, and a locking member having curved resilient arms inserted at their ends in opposite openings in the body adjacent one end thereof for permitting bodily movement of the locking member longitudinally of the body, said locking member being pivotable with respect to the body and releasably connectable at its free end to the corresponding free end of the body upon relative longitudinal movement of said body and locking member in one direction, the resilience of the arms of the locking member urging the member toward the body when the member is in locking position.

11. In a hair curling device, the combination of an elongated body, a lip hinged to the body adjacent one end thereof, a portion of said lip being normally urged against the side wall of the body, and a locking member pivotally connected at one end to the body adjacent the said one end thereof and releasably connectable at its free end to the corresponding free end of the body, said pivotable connection including a pin and slot combination to permit relative bodily movement

between said body and said locking member for connecting and disconnecting the free ends of the body and member.

12. In a hair curling device, the combination of an elongated body, a lip hinged to the body adjacent one end thereof, a portion of said lip being normally urged against the side wall of the body, and a locking member pivotally connected at one end to the body adjacent the said one end thereof and movable longitudinally relative to the body to effect a releasable connection at its free end to the corresponding free end of the body, said releasable connection including means on the free end of the locking member insertable in a recess in the free end of the body and movable longitudinally of the body with the member.

13. In a hair curling device, the combination of an elongated body, a locking member pivotally connected at one end to the body adjacent one end thereof and bodily movable longitudinally relative to the said one end of the body to effect a releasable connection at its free end to the corresponding free end of the body, said releasable connection including a reversely turned means on the free end of the locking member insertable in an opening in the free end of the body, and resilient means normally opposing longitudinal movement of said locking member relative to the body in the direction for effecting said releasable connection.
